UNITED STATES PATENT OFFICE.

CHESTER S. JENNINGS, OF BOSTON, MASSACHUSETTS, ASSIGNOR, BY MESNE ASSIGNMENTS, TO AMERICAN PNEUMATIC SERVICE COMPANY, OF BOSTON, MASSACHUSETTS. A CORPORATION OF DELAWARE.

STORE-SERVICE APPARATUS.

1,087,948.

Specification of Letters Patent. Patented Feb. 24, 1914.

Application filed June 24, 1908. Serial No. 440,078.

To all whom it may concern:

Be it known that I, CHESTER S. JENNINGS, citizen of the United States, residing at Boston, in the county of Suffolk and State of Massachusetts, have invented certain new and useful Improvements in Store-Service Apparatus; and I do hereby declare the following to be a full, clear, and exact description of the invention, such as will enable others skilled in the art to which it appertains to make and use the same.

The invention relates to store service apparatus, and more especially to that class of apparatus in which a basket or receptacle is detachably secured to a carrier mounted to travel on an elevated wire or way, and in which mechanism is provided at the end of the way for raising and lowering the receptacle to attach it to or detach it from the carrier.

It is the object of the invention to provide an apparatus of this type having its parts constructed and arranged in an improved and simplified manner.

To this end the invention contemplates the provision of improved mechanism for automatically locking the receptacle to the carrier when it is raised by the elevator mechanism, and for releasing the receptacle from the carrier and connecting it with the elevator mechanism when it is desired to detach and lower the receptacle.

The invention also contemplates the provision of improved means for preventing the despatching of the carrier from a station when the receptacle is detached from the carrier.

The invention also contemplates the provision of means for retaining the carrier at the end of the way in proper relation or register with the elevating mechanism when the receptacle is detached from the carrier, so that the proper operation of the locking devices when the carrier is raised by the elevating mechanism is secured.

The invention also contemplates the provision of improved means for applying a retarding or braking friction to the carrier as it approaches the ends of the way on which it travels.

The invention also includes certain further features and combinations, the advantages of which will be apparent to any one

skilled in the art from the following description of an apparatus embodying said features.

The various features of the invention will be readily understood from an inspection of the accompanying drawings, in which—

Figure 1 is an elevation showing an apparatus embodying the various features of the invention in their preferred forms; Fig. 2 is an enlarged sectional elevation showing the devices for locking the receptacle to the carrier, and for preventing the despatch of the carrier when the receptacle is not attached to the carrier; Fig. 3 is a transverse sectional view on line 3—3, Fig. 2; Fig. 4 is a bottom plan view of the parts shown in Fig. 2, the elevator stirrup being omitted; and Figs. 5 and 6 are detail views showing the locking devices in different positions.

In the apparatus shown in the drawings the way on which the carrier is adapted to travel in passing from one station to another consists of a wire 1 which is supported at its opposite ends from hangers 2 and 3 depending from the ceiling and secured in position in the usual manner. A wire 4 is arranged directly below and parallel to the way wire 1, and these wires are connected at one end to the opposite ends of a lever 5 which is mounted on a head plate 6, and at the other end are connected to tensioning devices (not shown) carried by a head plate 7, the points of attachment of the wires being such that the wires are held parallel to each other. The head plate 7 is pivotally connected at 8 to a bracket 9 which is adjustably secured upon the hanger 2. The head plate 6 is pivotally connected to a bracket 10 which is clamped upon a plate 11 carried by the hanger 3, the connection between the head plate and bracket being such that the head plate may move about a horizontal or vertical axis in accommodating itself to the position and adjustment of the wires 1 and 4.

The carrier comprises a frame 12 formed of two connected side plates which are provided with arms 13 arranged to extend upward on opposite sides of the wires 1 and 4, and carry wheels 14 which run upon the wire 1. The means for propelling the carriage along the way 1 consists of propelling cords arranged at each end of the way and

operated by the cashier or salesman as the case may be. The cashier's station is indicated at the left in Fig. 1, while the salesman's station is indicated at the right. The propelling cord 15 at the cashier's station is connected to an operating lever 16, pivoted upon an arm 17 of the head plate 6, and carrying pulleys 18 over which the propelling cord passes. The cord extends from the point 19 where it is attached to the lever over the pulley 20 mounted on the head plate 6, over one of the pulleys 18 on the lever 16, and over a pulley 21 on the head plate. From the pulley 21 the cord extends parallel to the wire 1, and passes over a pulley 22 mounted in a fork 23 at one side of the path of travel of the carrier. After passing over the pulley 22, the cord extends across to the other side of the plane of the wires 1 and 4, and thus across the path of the carrier 12, and passes around a second pulley 22 mounted in the fork 23, and thence over pulleys corresponding to pulleys 21, 18 and 20, and is attached at 19 to the operating lever 16. The fork 23 extends over the path of the pulleys 14 on the carrier 12, and is supported upon rods 24 to the outer ends of which the arms of the fork are secured. The inner ends of the rods 24 are secured in socket pieces 25 arranged on opposite sides of the path of travel of the carrier, and secured to the outer ends of tubes 26, the inner ends of which are secured to the head plate 6. The rods 24 and tubes 26 are in line with each other, so that the rod 24 may telescope within the tube 26 in adjusting the position of the fork 23. Each socket sleeve is provided with a vertical arm 27 which is connected by a stay rod 28 with a bracket sleeve 29 adjustably secured on the hanger 3.

The propelling cord 30 at the salesman's station is supported and arranged in the path of the carrier by devices similar to those by which the propelling cord is supported at the cashier's station. The ends of the cord are connected at 31 to a block 32 carrying two pulleys 33, and the cord extends from the points of attachment 31 over pulleys 34 mounted on the bracket 9, over the pulleys 33 on the block 32, over pulleys 35 mounted on the head plate 7. From the pulleys 35 the cord extends forward parallel to the wires 1 and 4, and passes over pulleys 36 carried in the arms of the fork 37, the cord extending from one pulley 36 to the other across the path of the carrier. An operating handle 38 is connected to the block 32, so that the salesman may readily operate the propelling cord in despatching the carrier. The fork 37 is secured on the outer ends of rods 39, the other ends of which are secured in socket sleeves 40. The socket sleeves are secured upon the outer ends of the tubes 41, the inner ends of which are secured to the head plate 7. The rods

39 may telescope within the tubes 41 in adjusting the fork 27 into the desired position.

The carrier is positioned at either end of the way on which it travels by means of latching devices which are constructed to cushion the carriage as it reaches the end of the way, and to retain the carriage in position until the propelling cord is operated, when the latching devices are disengaged to allow the carrier to move forward under the action of the propelling cord. These latching and cushioning devices in the form shown comprise stops 42 and 43 arranged at opposite ends of the way, and co-operating latch levers 44 and 45 on the carrier 12. The stop 42 is mounted in an arm 46 of the head plate 7, and is held in position by cushioning spring 47 and 48. The forward end of the stop is supported and held in proper relation with the wire 1 by engagement with the wire 4 which passes through an arm 49 of the stop. The latch 44 is provided with a bifurcated end, the arms of which are arranged to pass on opposite sides of the stop 42 and carry a roll 50 for engaging a retaining shoulder 51 on the stop. The latch 44 is pivoted on the carrier, and is provided with a vertical actuating arm 52 which is arranged to engage the propelling cord 30 as the carrier approaches the end of the way, and to draw the propelling cord into the position indicated in Fig. 1. The latch is held in normal position with a stop shoulder 53 on the latch in engagement with a shoulder 54 on the carrier by a spring 55 (Fig. 2).

When the salesman applies a pull to the cord 30 by drawing down on the handle 38, the cord, acting on the arm 52 of the latch lever, rocks the lever on its pivot in a direction to disengage the roll 50 from the shoulder 51, the rocking movement of the latch lever being limited by stops 56 which are arranged to engage the carrier. After the latch has been disengaged, the continued pull on the cord draws forward the loop of cord which extends from the pulleys 36 around the arm 52 on the carrier, and as the carrier is now free to move, this pull on the cord despatches the carrier and sends it to the other end of the way. As the carrier enters the cashier's station, the arm 52' of the latch lever 45 engages the cord 15 between the pulleys 22, and carries a loop of cord back into a position corresponding to the position of the cord 30 in Fig. 1. As the carrier reaches the end of the way, the roll on the latch 45 rides over the incline 57 on the stop 43 and drops behind the retaining shoulder on the stop, the stop yielding to cushion the carrier. When the carrier is to be returned, the lever 16 is depressed into the position indicated in Fig. 1. The pull thus exerted on the cord 15 first disengages the latch 45

and then despatches the carrier, so that it travels along the way and returns to the position indicated at the right in Fig. 1.

The detachable basket or receptacle in which the packages are transferred from one station to the other is indicated at 58, and is connected by bails 59 with a bail plate 60. An elevator mechanism for raising and lowering the basket is provided at the salesman's station, and devices are provided for automatically locking the basket to the carrier when it is raised by the elevator mechanism, and for automatically disengaging the basket from the carrier when it is desired to lower the basket. The elevator mechanism comprises a stirrup provided with a supporting bar 61, and two oppositely extending arms 62 to which the lower ends of the elevating cords 63 are secured. The cords pass up on opposite sides of the path of travel of the carrier, and are surrounded by flexible sleeves 64 which are secured in the stirrup arms, and are provided at their upper ends with caps 65. The upper ends of the sleeves are arranged to engage disks 66 which are mounted to slide in tubes 67, and are held at the bottoms of the tubes by coiled springs 68. The tubes 67 are adjustably secured in clamp sockets 69 formed in the socket sleeves 40, and are connected at their upper ends by a yoke 70 which extends from one tube to the other over the path of travel of the carrier wheels 14 (Fig. 3). The elevator cords 63 pass up through the tube 67 and over pulleys 71 mounted in the yoke 70, and from these pulleys pass up over pulleys 72 and are connected to a counter-weight 73. The weight 73 is sufficient to counter-balance the weight of the stirrup, and acts to hold the stirrup in the position indicated in Fig. 3 when the basket is supported and carried by the carrier. A rod or guard 74 is connected to the weight 73, and extends down to within convenient reach of the salesman, so that he may operate the elevator cords to raise and lower the basket. The pulleys 72 are mounted in a bracket 75 which is adjustably secured to the hanger 2. The yoke 70 and attached tubes and socket sleeves 40 are connected by a stay rod 76 with the bracket 75.

The carrier is provided with two depending arms 77 which form a transverse vertical slot 78 for receiving a cross-bar 79 formed on the bail plate 60. The lower ends of the arms 77 curve outward to form a flaring mouth for the slot 78, so that the bar 79 will be guided into the slot when the bail plate is raised. The bar 79 extends downward from the laterally extending arms 80 of the bail plate, and is provided with gauges 81 arranged to pass on opposite sides of the arms 77 on the carrier and hold the bail plate from lateral movement. The bar 79 is recessed at 82 to receive a locking pawl

83 which is mounted upon one end of the carrier arms 77. The locking pawl is in the form of a lever pivoted at 84 and arranged to normally extend across the slot 78, with its upper end resting against a stop shoulder 84' (Fig. 6). The locking pawl is held yieldingly in this position so that it will yield to allow the bar 79 to pass, and will then move forward into the recess 82 and below the upper section of the bar 79, and securely lock the bail plate to the carrier. 75

The means for disengaging the locking pawl from the locking bar comprises an actuating pawl 85 which is pivoted at 86 between the arms of a bifurcated lever 87, 80 which is in turn pivoted upon the pivot 84 for the locking pawl, the locking pawl being recessed at its lower end to receive the bifurcated lever. The two arms of the lever 87 are connected by a web 88. The lever is connected with the locking pawl by a spring 90' and is forced yieldingly forward by a spring 89 which is coiled about the pivot 84, and has one end connected with the plate 88 and the other end bearing against the carrier. The locking pawl is provided with a stop pin 90 arranged to be engaged by the upper end of the lever 87, so that the spring 89 tends to retain the locking pawl in position across the slot 78. The actuating pawl 85 is normally held by a spring 91 in position with its upper end resting against the upper part of the locking pawl, and its lower end to one side of the slot 78, as indicated in Fig. 6. 90

When the basket or receptacle is detached from the carrier, the bottom of the bar 79 rests upon the cross-bar 61 of the stirrup, as indicated in Fig. 6. When in this position, the receptacle is locked to the stirrup by means of a locking pawl 92 which is pivoted at its upper end in the bail plate 60, and is pressed yieldingly forward by a spring 93. The lower end of the pawl is provided with a hook 94 arranged to engage a pin 95 on one of the stirrup arms 62, the arm being recessed to receive the pawl 92. 105

When the carrier is in the position indicated at the right in Fig. 1 the slot 78 is in register with the elevator stirrup, so that the basket may be locked to or disconnected from the carrier by an upward movement of the stirrup. Assuming that the basket is detached, as indicated in Fig. 6, and it is desired to attach the basket to the carrier, the operator pulls on the lifting cords, thus moving the stirrup upward, the springs 68 yielding to allow this upward movement of the stirrup. As the bail moves upward, the bar 79 of the stirrup plate passes up into the slot 78, and the upper or locking section of the bar forces the locking pawl 83 back out of the slot 78 and passes above the end of the pawl. As soon as the locking bar has passed, the locking pawl swings forward through 110 115 120 125 130

the recess 82 and under the upper section of the bar, as indicated in Fig. 2. As the locking pawl moves into this position, the upper end of the actuating pawl 85 engages the locking bar on the bail plate, and the lower end of the actuating pawl is swung into the slot 78, as indicated in Fig. 2. When the stirrup is lowered into the position indicated in Fig. 2 to allow the despatching of the carrier, the lever 87 yields to allow the pivot 86 and the lower end of the actuating pawl to move outward to allow the passage of the stirrup. As soon as the stirrup has passed below the lower end of the actuating pawl, the lever 87 springs back into the position indicated in Fig. 2, bringing the lower end of the actuating pawl into the slot 78. When it is desired to disconnect the basket from the carrier, the stirrup is raised, and as it moves upward into the slot 78, the lower end of the actuating pawl 85 is engaged by an inclined surface 96 on the stirrup bar, and the pawl and its carrying lever 87 are swung outward into the position indicated in Fig. 5. During this outward movement of the actuating pawl and lever 87, the locking pawl 83 is still held in position by its engagement with the locking bar 79, the spring 90 yielding to allow the movement of the actuating pawl and its carrying lever with relation to the locking pawl, the tension on the spring being increased by the movement of the lever and pawl. After the stirrup engages the bottom of the bar 79, the continued upward movement of the stirrup carries the bar upward so that the locking pawl may swing into the position indicated in Fig. 5 under the influence of the spring 90. Now when the stirrup is lowered, the bail plate moves down with it, so that the locking bar is carried past the locking pawl and the basket is supported and carried by the stirrup. When the bail plate passes out of the slot 78 the parts return to the position indicated in Fig. 6, where they remain until the stirrup is again raised to connect the basket to the carrier.

When the bail plate is raised into position to be engaged and locked by the locking pawl, the latch 92 which locks the bail plate to the stirrup is disengaged from the pin 95 on the stirrup by means of cam ribs 97 formed on the arms 77 and arranged to engage arms 98 formed on the pawl (Figs. 3 and 4). When the stirrup is raised to disengage the basket from the carrier, the pin 95 on the stirrup is brought into position to be engaged by a hook 94 on the latch 92, and as the arms 93 ride off of the lugs 97 during the downward movement of the bail plate, the hooked end of the latch passes under the pin 95, thus automatically locking the basket to the stirrup.

In order that the basket may be securely retained upon the carrier, in case the lock-

ing devices should be imperfectly engaged, or should fail to operate properly, a supplementary or safety locking device is provided. This device comprises a locking lever 99 pivoted at 100 to the bail plate, 76 and provided with locking arms 101 arranged to overlie lugs 102 formed on the arms 77. The locking lever is pressed normally forward by a spring 103. When the basket is locked to the carrier, as indicated 76 in Figs. 2 and 3, the locking arms 101 engage the surfaces of the arms 77, and lie at some distance above the lugs 102. If for any reason the locking pawl 83 should not be properly engaged, and the basket should 80 fall, then the arms 101 on the locking lever 99 would come into engagement with the lugs 102, and would support the basket and prevent its detachment from the carrier. When the stirrup is raised to disconnect the 85 basket from the carrier, a pin 104 in one of the stirrup arms engages the lower end of the locking lever 99 and swings the lever outward so that the locking arms 101 pass free of the lugs 102 as the basket is lowered 90 with the stirrup.

When the basket is detached from the carrier and is supported and carried on the stirrup, the carrier should be retained so that it cannot be despatched until the basket 95 is again attached thereto, and should be retained in proper relation or register with the elevating mechanism so that the basket will be automatically locked to the carrier when it is raised by the elevating mechanism. The apparatus is accordingly provided with means for retaining the carrier at the end of the way and in register with the mechanism for raising and lowering the carrier whenever the basket or receptacle is 100 not attached to the carrier. This feature of the invention in its broader aspects contemplates the provision of any suitable means for thus retaining the carrier at the end of the way and preventing the despatch of the 110 carrier when the basket or receptacle is not attached thereto. In order, however, to avoid complication of parts, and to insure the retention of the carrier in accurate register with the mechanism for raising and 115 lowering the receptacle, the latching devices which cushion the carrier and retain it at the end of the way are utilized as a part of the mechanism for preventing the despatch of the carrier when the receptacle is detached, and means are provided for locking 120 these latching devices in engagement when the receptacle is detached from the carrier, and for allowing the disengagement of these devices when the receptacle is attached to 125 the carrier. In the construction shown, the devices for controlling the engagement and disengagement of the latching devices which 130 retain the carrier at the end of the way consist of locking levers 105 pivoted at 106 to

the carrier, and having their front ends arranged to be moved into and out of the path of stop pins 107 carried by the latch levers 44 and 45. The locking levers 105 are held in engagement with the arms 108 of actuating levers 109 by springs 110. The actuating levers 109 are yieldingly forced in a direction to lift the locking levers into position where they will engage the pins 107 and lock the latch levers 44 and 45 in position by springs 111. The ends of the levers 109 are arranged to be engaged and operated by a pin 112 mounted on the carrier, and extending down into the slot 78.

15 When the bail plate is locked to the carrier, as indicated in Fig. 2, the locking bar 79 engages the pin 112 and holds it in its upper position so that the locking levers 105 are retained in the position indicated in 20 full lines in Fig. 2. When in this position, the locking levers do not interfere with the movement of the latching levers when the propelling cord is operated to despatch the carrier. When the bail plate is disengaged 25 from the carrier, the pin 112 drops to the position indicated in Fig. 6, and the levers 105 are swung up into the dotted line position in Fig. 2, where their free ends are back of the pins 107 and prevent the rocking of the latch levers when a pull is exerted on 30 the propelling cords, and thus prevent the despatching of the carrier or the movement of the carrier out of register with the elevating mechanism until the basket has been 35 attached to the carrier. The devices for retaining the carrier in position at the end of the way are thus controlled by the receptacle, and it is necessary that the receptacle be attached to the carrier in order that the carrier may be despatched or may be moved 40 out of proper register with the elevating mechanism.

45 In order that the carriage may be retarded as it approaches the ends of the way on which it travels, the carriage is provided with surfaces arranged to deflect the wires 1 and 4 as the carriage approaches the end of the way, and thus frictionally retard the carriage. In the construction shown, the 50 wheels 14 are utilized as surfaces for engaging the wire 1, and the carriage is provided with friction blocks 113 for engaging the wire 4, the space between the blocks and wheels being less than the spacing of the wires, so that the blocks and wheels coöperate to deflect the wires, and to frictionally retard the carriage as it approaches the end 55 of the way. During the travel of the carriage along the way between stations, the 60 sag of the wire 1 is such that there is no braking or retarding effect produced by the engagement of the wires with the opposing surfaces formed by the wheels 14 and the friction blocks 113.

65 Having set forth the nature and object of

the invention, and specifically described one form of apparatus in which it may be embodied, what I claim is:—

1. A store service apparatus, having, in combination, a carrier provided with a vertical slot, a receptacle provided with a locking bar adapted to enter the slot when the receptacle is raised, a locking pawl pivoted at one side of the slot, and means for yieldingly holding the pawl across the slot so 70 that the pawl will yield as the bar enters the slot and then pass across the slot beneath the bar, the bar being free to move in the slot above the pawl clear of the latter, substantially as described.

2. A store service apparatus, having, in combination, a carrier provided with a vertical slot, a receptacle provided with a locking bar adapted to enter the slot when the receptacle is raised, a locking pawl pivoted 75 at one side of the slot, means for yieldingly holding the locking pawl across the slot so that the pawl will yield as the bar enters the slot and then pass across the slot beneath the bar, the bar being free to move in the 80 slot above the pawl clear of the latter, an actuating part for disengaging the locking pawl from the locking bar, and means for holding the actuating part out of the path of the locking bar when the receptacle is detached from the carrier and with a portion 85 thereof projecting into the slot in said path when the receptacle is attached to the carrier, substantially as described.

3. A store service apparatus, having, in 90 combination, a way, a carrier adapted to travel thereon provided with a vertical slot, a receptacle provided with a locking bar adapted to enter the slot when the receptacle is raised, a locking pawl pivoted at 95 one side of the slot, means for yieldingly holding the locking pawl across the slot so that the pawl will yield as the bar enters the slot and then pass across the slot beneath the bar, the bar being free to move 100 in the slot above the pawl clear of the latter, latching devices for retaining the carrier at the ends of the way, and means for locking the latches operated by the movement of the locking bar in the slot above the 105 locking pawl, substantially as described.

4. A store service apparatus, having, in combination, a way, a carrier adapted to travel thereon provided with a vertical slot, a detachable receptacle provided with a 110 locking bar adapted to enter the slot when the receptacle is raised, a locking pawl pivoted at one side of the slot, means for yieldingly holding the locking pawl across the slot so that the pawl will yield as the bar 115 enters the slot and then pass across the slot beneath the bar, the bar being free to move in the slot above the pawl clear of the latter, latching devices for retaining the carrier at the ends of the way, locking levers 120

for preventing the disengagement of the latching devices, and levers for actuating the locking levers operated by the movement of the locking bar in the slot above the locking pawl, substantially as described.

5. A store service apparatus, having, in combination, a carrier, a detachable receptacle, a locking pawl arranged to automatically lock the receptacle to the carrier and to be locked thereby, an elevator for raising and lowering the receptacle, an actuating pawl held in position to be operated by the upward movement of the elevator when the receptacle is locked to the carrier, and a 10 spring connection through which the locking pawl is actuated when released by the receptacle, substantially as described.

6. A store service apparatus, having, in combination, a carrier, a detachable receptacle, an elevator for raising and lowering the receptacle, a locking mechanism, said receptacle provided with a part adapted for locking engagement with said mechanism, said mechanism comprising a locking member held yieldingly in position to engage and lock said part of the receptacle when operatively disposed with respect thereto, an actuating member for disengaging said locking member from said part and provided with means for retaining said actuating member in position to be engaged by a part of the elevator when the receptacle is locked to the carrier, and means, including a resilient connection between said members, whereby the actuating member, when so engaged by said part of the elevator, may effect said disengagement of said locking member from said part of the receptacle, substantially as described.

40. 7. A store service apparatus, having, in combination, a carrier, a detachable receptacle, an elevator for raising and lowering the receptacle, a locking pawl arranged to automatically lock the receptacle to the carrier, an actuating pawl held in inactive position when the receptacle is detached from the carrier, means for holding said actuating pawl in position to be engaged by the elevator when the receptacle is locked to the 45 carrier, and means, including a resilient connection between said pawls, for disengaging said locking pawl from said receptacle when said actuating pawl is operatively engaged by said elevator and the latter is elevated.

8. A store service apparatus, having in combination, a carrier provided with a vertical recess, a detachable receptacle provided with a bar for entering said recess, an elevator for raising and lowering the receptacle, a locking pawl yieldingly held in said recess, an actuating pawl, a carrying lever on which the actuating pawl is yieldingly pivoted, a 50 spring connection between the carrying lever and locking pawl, and means for holding

a part of the actuating pawl in the path of a part of the elevator when the receptacle is locked to the carrier, substantially as described.

9. A store service apparatus, having, in combination, a carrier provided with a vertical slot, a detachable receptacle provided with a bar for engaging the slot, an elevator for raising and lowering the receptacle, a locking pawl pivoted to the carrier, an 75 actuating pawl having its upper end arranged to be engaged by the locking bar on the carrier and its lower end arranged to be to one side of the slot in the carrier when the receptacle is detached from the carrier, 80 and to be projected into the slot when the upper end of the pawl is engaged by the locking bar, and connections between the actuating pawl and locking pawl for disengaging the locking pawl, substantially as described. 85

10. A store service apparatus, having, in combination, a carrier, a detachable receptacle, a locking mechanism comprising a locking pawl 84, an actuating pawl 85, a carrying lever 87 upon which the actuating pawl is pivotally mounted, and springs for yieldingly holding the pawls and lever in normal position and for yieldingly connecting the actuating and locking pawls, substantially as described. 95

11. A store service apparatus, having, in combination, a carrier provided with a vertical slot, a receptacle provided with a locking bar adapted to enter the slot when the receptacle is raised, a locking pawl pivoted 100 at one side of the slot, a stop shoulder on the other side of the slot, means for yieldingly holding the locking pawl across the slot and in engagement with the shoulder so that the pawl will yield as the bar enters the slot 105 and then pass across the slot beneath the bar, substantially as described.

12. A store service apparatus, having, in combination, a carrier provided with a vertical slot, a receptacle provided with a locking bar adapted to enter the slot when the receptacle is raised, a locking pawl pivoted at one side of the slot, a stop at the other side of the slot, means for yieldingly holding the locking pawl across the slot and in 115 engagement with the stop shoulder, an actuating pawl for disengaging the locking pawl from the locking bar, means for holding said actuating pawl out of the path of the locking bar when the receptacle is detached from the carrier and with its lower end projecting into the slot when the receptacle is attached to the carrier, substantially as described. 120

13. A store service apparatus, having, in combination, a way, a carrier adapted to travel thereon and provided with a vertical slot, a receptacle provided with a locking bar adapted to enter said slot, a locking pawl held yieldingly across the slot in po- 125

sition to allow the introduction and prevent the withdrawal of the locking bar, latching devices for retaining the carrier at the end of the way, means for locking the latches operated by the locking bar when the receptacle is attached to the carrier, substantially as described.

14. A store service apparatus, having, in combination, a way, a carrier adapted to travel thereon, a detachable receptacle, latching devices for retaining the carrier at the end of the way, locking levers for preventing the disengagement of the latching devices, actuating levers arranged to be operated by the receptacle when attached to the carrier, and yielding connections between the actuating levers and latching levers, substantially as described.

15. A store service apparatus, having, in combination, two parallel wires, a carrier mounted to travel on one of said wires, and wire engaging surfaces on the carrier arranged to deflect the wires as the carrier approaches the end of the wires to frictionally retard the carrier, substantially as described.

16. A store service apparatus, having, in combination, two parallel wires, a carrier provided with supporting wheels arranged to travel on one of said wires, and a surface on the carrier arranged to engage the other wire and coöperating with the wheels to deflect the wires out of parallelism as the carrier approaches the end of the way, and to frictionally retard the carriers, substantially as described.

17. A store service apparatus, having, in combination, two parallel wires, a carrier provided with wheels arranged to travel on one of said wires, a friction plate engaging the other wire, the space between the plate and wheel being less than the spacings of the wires, substantially as described.

18. A store service apparatus, having, in combination, two parallel wires arranged one above the other, a carrier provided with wheels arranged to travel upon the upper wire, and friction plates engaging the lower wire and arranged at a distance below the wheels less than the spacing of the wires, substantially as described.

19. A store service apparatus, having, in combination, a way, a carrier mounted to travel on the way, a head plate for supporting the way, tubes extending parallel with the way on opposite sides of the path of the carrier, socket sleeves secured to the ends of the tubes, telescoping rods adjustably secured to the socket sleeves, a fork secured to the ends of the rods, and a propelling cord supported in the path of the carrier by the fork, substantially as described.

20. A store service apparatus, having, in combination, a way, a carrier adapted to

travel on the way, a head plate for supporting the way, tubes secured to the head plate and extending parallel with the way on opposite sides of the path of the carrier, socket sleeves secured to the ends of the tubes, elevator cords, and supporting devices for the elevating cords secured in the socket sleeves, substantially as described.

21. A store service apparatus, having, in combination, a way, a carrier adapted to travel on the way, a detachable receptacle, mechanism for raising and lowering the receptacle, devices for automatically locking the receptacle to the carrier when raised, a supplemental locking lever on the receptacle provided with a locking arm arranged to overlie a shoulder on the carrier when the receptacle is locked to the carrier by the main locking devices, and a device on the elevating mechanism for engaging the lower end of the lever and swinging it free of the shoulder when the receptacle is carried by the elevating mechanism, substantially as described.

22. A store service apparatus, having, in combination, a way, a carrier mounted to travel on the way, a detachable receptacle, an elevator for raising and lowering the receptacle, devices for automatically locking the receptacle to the carrier when raised by the elevator, and for unlocking the receptacle when the elevator is raised without the receptacle, a locking pawl on the receptacle for engaging the elevator and locking the receptacle thereto, and means on the carrier for disengaging the locking pawl from the elevator when the receptacle is in position to be locked to the carrier, substantially as described.

23. A store service apparatus, having, in combination, a carrier, a detachable receptacle, an elevator for raising and lowering the receptacle, devices for locking the receptacle to the carrier when raised by the elevator, and for unlocking the receptacle when the elevator is raised without the receptacle, a spring-pressed locking pawl pivoted on the receptacle, and a cam on the carrier for disengaging the pawl from the elevator when the receptacle is raised into position to be locked to the carrier, substantially as described.

24. A store service apparatus, having, in combination, a carrier and a receptacle adapted to be attached to said carrier, one of said parts being provided with a vertical recess and the other of said parts being provided with a locking element adapted to be entered into said recess when the receptacle is raised toward the carrier, a member adapted for engagement with said locking element and mounted adjacent the walls of said recess, and means for yieldingly but definitely holding a part of said member in the recess in substantially vertical alignment with said locking element so that said mem-

ber will yield as said element is introduced into said recess and thereafter be disposed in said recess normally in substantial juxtaposition to said element whereby to prevent separation of said receptacle from said carrier, said element being free thereafter for further entry into said recess relatively away from said member, and clear of the latter, said holding means adapted to position said member in said recess in the definite manner above referred to, substantially regardless of the angle with respect to the horizontal at which said carrier may happen to be disposed, an elevator for raising and lowering said receptacle, and means connecting with said elevator for releasing said locking element from said member when said element is at such time entered farther into said recess in manner aforesaid.

25. A store service apparatus, having, in combination, a carrier provided with a vertical slot, a receptacle provided with a locking bar adapted to enter the slot when the

receptacle is raised, a locking pawl pivoted at one side of the slot, means for yieldingly holding the locking pawl across the slot so that the pawl will yield as the bar enters the slot and then pass across the slot beneath the bar, the bar being free to move in the slot above the pawl clear of the latter, an actuating part separate and distinct from said pawl for disengaging the locking pawl from the locking bar, and means for holding the actuating part out of the path of the locking bar when the receptacle is detached from the carrier and with a portion thereof projecting into the slot in said path when the receptacle is attached to the carrier, substantially as described.

In testimony whereof I affix my signature, in presence of two witnesses.

CHESTER S. JENNINGS.
